INFLATABLE PLAY PEN

Daniel S. J. Choy, 170 E. 77th St., and Gloria S. Vickery,
78 W. 12th St., both of New York, N.Y.

Filed Dec. 19, 1962, Ser. No. 72,898

Term of patent 14 years

(Cl. D5—5)

FIG. 1.

FIG. 2.

FIG. 4.

FIG. 3.

FIG. 2 is a top plan view,

FIG. 3 is a side elevational view, and

FIG. 4 is a cross sectional view taken on line 4—4 of FIG. 3.

We claim:

The ornamental design for an inflatable play pen, substantially as shown.
